ELECTROMAGNETIC TRACTION INCREASER

David E. Wehner, Allison Park, Pa.

Application December 2, 1936, Serial No. 113,940

1 Claim. (Cl. 105—77)

This invention relates to apparatus for railroads whereby to have magnetized rims on the wheels of railroad locomotives and cars whereby to have traction and stick to a magnetic rail.

5 In the accompanying drawing forming part of this specification:

Figure 1 is a longitudinal view of an apparatus constructed in accordance with the invention, showing in cross section the electromagnetic 10 helix.

Figure 2 is an end view of the frame and wheel and shows a cross section of the rail, and also the spikes.

15 Figure 3 is a top plan view of the wheel, frame, rail, spikes, and shows part of the electromagnetic helix.

Figure 4 is a transverse vertical cross sectional view of wheel, frame, tie, and the electromagnetic helix, and magnetic rail showing the associated 20 nonmagnetic spikes.

Referring to the numbers in the drawing which designate characters of reference, 41a designates a frame which can be clamped to any axle frame on a railroad locomotive or railroad car and 25 which frame fits on the wheel axle as designated by reference numeral 51, to the axle frame on the locomotive or car longitudinal to make it rigid and to hold the electromagnetic helix in lateral and longitudinal position to clear the magnetic 30 rail and wheel. 39a and 40a designate members attached to the frame 41a and being of one piece of material which incloses the lower and outside portions of the electromagnetic helix 37, and which support the electromagnetic 35 helix 37. 36 designates the wheel for a railroad wheel truck which is nonmagnetic, the flange being nonmagnetic whereby to prevent lateral attraction by magnetism and binding on the rail, and it being understood that the wheel and flange 40 are formed of nonmagnetic substance similar to any common wheel and of which said wheel fits tight on axle 51. 38a designates a rim of permanent magnetic substance which fits tight on over the wheel and against the flange and which 45 by magnetic induction from the electromagnetic helix 37 forms a magnetic attraction between the rim and the rail 38, and it being understood that the rim is similar to any common type rim and being pressed on the wheel. 37 designates an electromagnetic helix which surrounds the lower

portion of the wheel as shown in Figures 1 and 4 spaced from the rail and giving clearance for the wheel to revolve. Said helix is held in place by structural members 39a and 40a which extend from frame 41a. 38 designates a rail which is 5 magnetic. 44 is a rheostat which can be located at any convenient place on the railroad locomotive or railroad car with which the invention is associated. The electric lead lines 45 and 46 carry the current to the helix 37 to control the 10 electromagnetic intensity. 57 designates a nonmagnetic spike which secures the rail to tie 55 whereby preventing attraction thereof by the magnetized rim. 55 designates the tie which supports the rail and it being understood that the tie 15 is similar to any common railroad track tie.

In operation the electromagnetic helix is energized by electrical current controlled by rheostat 44 which regulates the electromagnetic intensity and forms a magnetic flux through the 20 portion of the permanent magnetic rim which has magnetic properties. Further the magnetized rim attracts the magnetic rail perpendicularly which increases the traction between the rail and the wheel. The nonmagnetic flange prevents 25 lateral attraction to the side of the rail by magnetism and binding on the rail. The nonmagnetic wheel prevents magnetic resistance. And when the electromagnetic helix is de-energized the permanent magnetic rim loses its magnetism 30 to the point of its residual magnetism, and the residual and permanent magnetism of the said rim attracts the magnetic rail to increase traction and to stay on the rail. The associated rail spikes being nonmagnetic, prevent attraction by 35 the magnetized rim.

I claim:

In combination in a railroad car, a permanent magnetic rim on a non-magnetic wheel having a non-magnetic flange, an electromagnetic helix 40 supported by the car and positioned closely adjacent to the lower portions of the said wheel and adapted to be supplied with car carried current, said helix when energized, increasing the magnetism of the said rim for magnetic attraction 45 to a magnetic track rail supporting said wheel for rotary movement thereof, thereby increasing adhesion between said track rail and said wheel.

DAVID E. WEHNER. 50
